(57) **CLAIM**

The ornamental design for a remote control docking station, as shown and described.

DESCRIPTION

FIG. 1 shows a right side view of the remote control docking station including the moveable assembly shown in a first position wherein a remote control is shown prior to docking.

FIG. 2 shows a right side view of the remote control docking station wherein a remote control is shown docketed to the moveable assembly.

FIG. 3 shows a front perspective view of a remote control docking station including a moveable assembly.

FIG. 4 shows a front view of a remote control docking station including a moveable assembly.

FIG. 5 shows a front view of the remote control docking station wherein a remote control is shown docketed to the moveable assembly.

FIG. 6 shows a back perspective view of a remote control docking station including a moveable assembly.

FIG. 7 shows a back view of a remote control docking station including a moveable assembly.

FIG. 8 shows a left side view of a remote control docking station including a moveable assembly, the moveable assembly shown in a first position.

FIG. 9 shows a left side view of a remote control docking station including a moveable assembly, the moveable assembly shown in a second position; and,

FIG. 10 shows a bottom view thereof.

The broken line showing of the environment and portions of the docking station in FIG. 10 are for illustrative purpose only and forms no part of the claimed design.
